FIG. 1.

FIG. 2.

FIG. 3.

Inventor
W. O. Seydel
N. M. Wilson

Attorney

UNITED STATES PATENT OFFICE.

WILLIAM OSEYCHUK, OF ALLENTOWN, PENNSYLVANIA.

TOY.

1,314,205.

Specification of Letters Patent. Patented Aug. 26, 1919.

Application filed February 14, 1919. Serial No. 277,017.

To all whom it may concern:

Be it known that I, WILLIAM OSEYCHUK, a citizen of Ukraine, residing at Allentown, in the county of Lehigh and State of Pennsylvania, have invented certain new and useful Improvements in Toys, of which the following is a specification.

The primary object of the invention is the provision of a toy in the nature of a 10 gymnast whereby a figure or rough representation of a human being is caused to perform in various ways upon a horizontal bar member, the antics of the figure being produced and controlled by pressure exerted by the hand of the operator.

15 A further object of the invention is the provision of an automaton having a normal depending position and adapted for performing movements or antics similar to those of a gymnast upon a trapeze or horizontal bar, such operation being easily and quickly accomplished by the person in charge of the device.

With these general objects in view the 20 invention consists of the combination and arrangement of parts hereinafter fully described in connection with the accompanying drawing and in which like reference characters designate corresponding parts throughout the several views.

30 In the drawings,

Figure 1 is a front elevation of the invention in its normal position members being illustrated by dotted lines in their adjusted positions and with parts broken away.

Fig. 2 is a side elevation thereof with one side member broken away and

Fig. 3 is a view similar to Fig. 1, of a 40 slightly modified form of construction.

My invention primarily consists of a frame having opposite side bars 10 and 11 connected together adjacent their upper ends by a flexible cord 12 in the form of a 45 loop extending through the said bars as well as through the spaced arms 13 of a doll or figure, 14. The arms 13 of the doll are pivotally connected to the body of the doll while legs 15 are swingingly carried 50 thereby in a similar manner.

A brace 16 connects the side bars 10 and 11 substantially centrally, one end of the brace being pivoted as at 17 to the side bar 11 while an opposite reduced end 18 of the 55 brace freely extends through an opening 19 in the opposite bar 10. A spring 20 upon

the reduced end 18 of the brace 16 between the bar 10 and a shoulder 21 of the brace normally maintains the bar 10 engaging a stop pin 22 extending through the brace 60 portion 18.

A second brace 23 is provided at the opposite end of the device from the cord 12 being pivoted at one end within a slot 24 in the bar 11 while the opposite reduced 65 end 18' of the brace 23 freely extends through a perforation 19' oppositely positioned in the bar 10 and a spring 20 between the bar 10 and shoulder 21' of the brace 23 normally retains the bar 10 engaging a stop pin 22' positioned through the brace portion 18' outwardly of said bar 10'. The normal position of the device is illustrated in Fig. 1 of the drawing and by grasping the bars 10 and 11 in the hand at 70 a point between the braces 16 and 23, the lower ends of the bars may be drawn toward each other by tilting the bar 10 as illustrated by dotted lines. This action causes the twisted cord 12, to straighten out 75 in the form of a rectangular loop thereby reversing the vertical direction of the doll's arms 13 and carrying the body and legs of the doll along with the arm. Upon releasing the pressure upon the bars 10 and 11, 80 the springs 20' as well as the weight of the doll 14, upon the cord 12, will cause the bar 10 to return to its normal position parallel with the opposite bar 11. By alternately drawing the lower portion of the bar 10 toward the bar 11 and releasing the same, the 85 doll 14 will be caused to rise and swing over the cord 12 after the manner of a gymnast performing upon a horizontal bar and the antics of the doll may be readily controlled 90 at the pleasure of the operator.

In Fig. 3 of the drawing, the doll 14' is provided with pivoted legs 15' while its arms 13' are carried by the cord 12' secured through the side bars 10' and 11' adjacent 100 one end of the device in a manner identical to that illustrated in Fig. 1. A single cross brace 16' is provided in this form of the invention with one end of said brace fixed as at 25 in the side bar 11. The reduced 105 opposite end 18'' of the brace freely extends through an opening 19'' in the opposite bar 10' while a spring 20'' mounted upon the brace portion 18'' holds the bar member 10' in normal engagement with the stop pin 22'' 110 adjacent the outer end of the brace. By drawing the lower free ends of the bars 10'

and 11' toward each other, the cord 12' is caused to straighten out and upon releasing the pressure upon said bars, the weight of the doll will return the bars and doll to their 5 normal positions.

An amusing toy is provided in both forms of the invention that is easily operated and is normally positioned ready for use.

In the preferred embodiment of the invention shown in Figs. 1 and 2 of the drawings, the spring 20⁷ is preferably weaker than the spring 20 so that the invention will operate as herein described no matter where the pressure of the hand is exerted, 10 upon the bars 10 and 11 at any point between the braces 16 and 23 although better results may be obtained by engaging the said bars at points adjacent the end brace 23.

What I claim as new is:—

20 1. A toy comprising side bars, a looped cord adapted to assume rectangular shape connected between the ends of the bars at one end of the device, a doll figure comprising a body having pivoted legs and arms 25 with the arms freely positioned upon the loop, a substantially centrally positioned brace between said bars having swinging

connection with each of the bars and a shield portion adjacent one end, a brace at the opposite end of the device from said 30 cord pivoted to the bar and slidably positioned with a shoulder adjacent the same through the opposite bar and resilient means upon said braces between said shoulders and bars adapted for normally maintaining 35 the bars parallel.

2. A toy comprising opposite bars, a flexible member connected between adjacent ends of said bars, a doll swingingly carried by said flexible member adapted for changing 40 its position during the straightening and the twisting of said flexible member, a brace pivotally connected substantially centrally between said bars, an end brace pivoted to one of said bars adjacent the opposite 45 end thereof from said cord and having a reduced end freely projecting through the opposite bar and a spring surrounding said end bearing against the adjacent bar whereby the bars are normally maintained parallel with the doll figure suspended therebetween.

In testimony whereof I affix my signature.
WILLIAM OSEYCHUK.
